Primary Examiner — Richard E Chilcot(74) *Attorney, Agent, or Firm* — Alfred M. Walker(57) **CLAIM**

I claim the ornamental design for a toy railroad engine vehicle flashlight, as shown and described.

DESCRIPTION

FIG. 1 is a perspective view of a preferred embodiment for a toy railroad engine vehicle flashlight, showing a “railroad steam engine” vehicle;

FIG. 2 is a right side elevation view thereof;

FIG. 3 is a left side elevation view thereof;

FIG. 4 is a front elevation view thereof;

FIG. 5 is a rear elevation view thereof;

FIG. 6 is a top plan view thereof; and,

FIG. 7 is a bottom thereof.

The details of the railroad engine boiler, cow catcher, smokestack, wheels, and operator's cabin are shown for environmental purposes in dashed lines, and form no part of the claimed design.
